United States Patent Office

Des. 186,080
Patented Sept. 8, 1959

186,080

TOY CROSS BOW

Simon Philp, Jr., Houston, Tex.

Application August 18, 1958, Serial No. 52,244

Term of patent 3½ years

(Cl. D34—15)

Fig. 1 is a side view of the toy cross bow; and
Fig. 2 is a top plan view of the toy cross bow.

I claim:

The new and ornamental design for a toy cross bow,
substantially as shown.
